UNITED STATES PATENT OFFICE

WILLIAM ANDREW UTTZ, SR., OF LAKewood, OHIO

DESIGN FOR AN ILLUMINATED ADVERTISING PACKAGE-SEALING-MACHINE CASING

Application filed October 19, 1929. Serial No. 33,109. Term of patent 14 years.

To all whom it may concern:

Be it known that I, WILLIAM ANDREW UTTZ, SR., a citizen of the United States, residing at Lakewood, in the county of Cuyahoga and State of Ohio, have invented a new, original, and ornamental Design for an Illuminated Advertising Package-Sealing-Machine Casing, of which the following is a specification, reference being had to the accompanying drawing, forming part thereof.

In the drawings Fig. 1 is a perspective of the front of the machine casing showing the top end and one side thereof; Fig. 2 is a perspective of the rear of the machine, showing the rear end and the other side thereof.

I claim

The ornamental design or an illuminated advertising package sealing machine casing, as shown.

In testimony whereof I affix my signature.

WILLIAM ANDREW UTTZ, SR.
